DESIGN FOR A HAT

Mina A. Alexander, New York, N. Y.

Application June 23, 1941, Serial No. 101,616

Term of patent 3½ years

To all whom it may concern:

Be it known that I, Mina A. Alexander, a citizen of the United States, residing in New York city, in the county of New York and State of New York, have invented a new, original, and ornamental Design for Hats, of which the following is a specification, reference being had to the accompanying drawing, forming part thereof, in which—

I claim:

The ornamental design for a hat, as shown.

MINA A. ALEXANDER.
